UNITED STATES PATENT OFFICE.

BENJAMIN F. METZ, OF MEDWAY, OHIO, ASSIGNOR TO HIMSELF AND JOHN KAUFFMANN, OF SAME PLACE.

CAR-COUPING.

SPECIFICATION forming part of Letters Patent No. 271,501, dated January 30, 1883.

Application filed November 24, 1882. (No model.)

To all whom it may concern:

Be it known that I, BENJAMIN FRANKLIN METZ, of Medway, in the county of Clarke and State of Ohio, have invented a new and Improved Car-Coupling, of which the following is a full, clear, and exact description.

The invention has for its object to improve the usual means for uncoupling the pivoted wings of a draw-head from an arrow-head link 10 and for holding the link up in front, so as to be conveniently guided into an opposite draw-head, as hereinafter described.

Reference is to be had to the accompanying drawings, forming part of this specification, in 15 which similar letters of reference indicate corresponding parts in all the figures.

Figure 1 is an end elevation of my improved car-coupler, parts being shown in section. Fig. 2 is a plan view of the same, showing one kind 20 of draw bar or link. Fig. 3 is a sectional plan view of the same, showing another draw bar or link.

The draw-head A is provided with an inwardly-tapering end opening in the usual manner, and behind the same the opening in the draw-head is straight, and provided in each side with a recess or groove, A', adapted to receive wings B B', placed edgewise and adapted to swing laterally, and rigidly mounted on 25 vertical shafts C C', journaled in the top and bottom of the draw-head, the upper ends of the shafts projecting from the top of the draw-head. Hooks D D', projecting toward each other so that the point of one rests against the 30 shank of the other, are rigidly mounted on the upper ends of the shafts C C'. The hook D is provided with an arm, E, to the end of which an angle-lever, F, is pivoted, the outer end of the said angle-lever being pivoted to a horizontal movable rod, G, which is suitably guided, and extends to the side of the car. A lever, H, pivoted to the rod G, extends to the top of the car, which lever H is suitably fulcrumed at h. The inner end of the angle-lever F is 35 above a vertically-sliding pintle, J, in the top of the draw-head, which pintle is provided at its upper end with a head, K. The pintle is pressed upward by a spring, L, surrounding it. Springs M, attached to the draw-head at 40 the inner end of its opening, have their free

ends resting against the outer surface of the free ends of the wings B B' and press the free ends of the said wings toward each other, the said springs passing into grooves A² in the inner sides of the draw-head.

The draw bar or link N is provided at both ends with arrow-heads a, or at one end with an arrow-head, a, and at the other with a loop or eye, b, which latter modification is to be used if a car having the usual draw-head is to be 55 coupled to a car provided with my improved draw-head. The links can be straight or curved to adapt them for coupling cars of different heights. The draw bar or link is provided with a cross-rod, O, to prevent inserting the 60 draw-bar too far in the draw-head.

The operation is as follows: The cars are coupled automatically, for if the end of the draw-bar enters the draw-head it presses the wings B B' laterally until the arrow-head has 65 passed. Then the springs M hold the ends of the wings B B' against the shank of the draw-bar, and prevent the latter from being withdrawn, as the shoulders of the draw-head strike against the ends of the wings. If the 70 cars are to be uncoupled, the rod G is drawn in the direction of the arrow a'—that is, toward the side of the car, either directly from the side of the car or from the top—by means of the lever H. Thereby the shafts C C' will 75 be turned in the direction of the arrows and the wings B B' will be swung from each other, thus permitting the draw-bar to be withdrawn. If the rod G is moved in the inverse direction of the arrow a', the inner end of the angle-lever F will be pressed on the head of the pintle J, and the pintle J will be pressed down into the draw-head, and will depress the inner end of the draw-bar, the outer end of which will be 80 raised. The same can be raised more or less, 85 as may be required, to guide it into the opposite draw-head.

It will be seen that the link-heads a, being wider than the slots A² for the springs M, will always be freely guided by the side walls of 90 the rear chamber of the draw-head, and without liability of catching therein, as in other draw-head constructions.

I am aware that it is not new to use pivoted wings with an arrow-head link in coupling 95

cars, or to employ vertical or horizontal bars or levers for disconnecting the coupling from the link; but

What I do claim as new and of my invention is—

1. The combination, with rocking wing-carrying shafts C C', of the interlocking arms D D', attached thereto as described, whereby the wing-shafts are so connected that the turning 10 of one turns both, as described.

2. The combination, with the draw-head A, of the shafts C C', the wings B B', the hooks D D', a rod for turning one of the shafts, and of the springs M, substantially as herein shown 15 and described, and for the purpose set forth.

3. The combination, with the draw-head A, of the shafts C C', the wings B B', the springs M, the hooks D D', the arm E, and the rod G, substantially as herein shown and described, 20 and for the purpose set forth.

4. The combination, with the draw-head A, of the shafts C C', the wings B B', the springs M, the hooks D D', the arm E, the angle-lever F, the rod G, and the pintle J, extending 25 through the top of the draw-head, substantially as herein shown and described, and for the purpose set forth.

5. The combination, with the draw-head A, of the shafts C C', the wings B B', the springs 30 M, the hooks D D', the arm E, the angle-lever

F, the rod G, the pintle J, the head K, and the spring L, substantially as herein shown and described, and for the purpose set forth.

6. The combination, with the draw-head A, of the shafts C C', the wings B B', the springs 35 M, the hooks D D', the arm E, the angle-lever F, the pintle J, the head K, the spring L, the rod G, and the lever H, substantially as herein shown and described, and for the purpose set forth. 40

7. A car-coupling provided with the upwardly spring-pressed slide-pintle J, extending through the top of draw-head, whereby pressure on the top of said pintle may force down the rear end of the coupling-link, so as to raise 45 the front end and guide it into an opposing draw-head, as described.

8. The combination, with a spring-pintle, J, projecting through the top of draw-head, of a lever, F, fulcrumed on the top of draw-head, 50 extending over the pintle and connecting by a pivot-joint with a hand-rod, G, whereby pressure may be brought to bear on the top of said pintle by pushing the rod G inwardly toward the draw-head, as described.

BENJAMIN FRANKLIN METZ.
